UNITED STATES PATENT OFFICE.

EDWARD S. PLIMPTON, OF DENISON, IOWA.

MECHANISM FOR CONVERTING MOTION.

SPECIFICATION forming part of Letters Patent No. 274,374, dated March 20, 1883.

Application filed October 24, 1882. (No model.)

To all whom it may concern:

Be it known that I, EDWARD S. PLIMPTON, of Denison, in the county of Crawford and State of Iowa, have invented a new and Improved Mechanism for Converting Motion, of which the following is a full, clear, and exact description.

The object of my invention is to provide mechanism for converting the reciprocating motion of windmill pitman-rods into continuous and steady rotary motion without dead-centers; and to that end the invention consists in lever mechanism constructed and arranged as hereinafter described and claimed.

Reference is to be had to the accompanying drawings, forming part of this specification, in which similar letters of reference indicate corresponding parts in both the figures.

Figure 1 is a side elevation of the mechanism, and Fig. 2 is a sectional plan view on line $x x$ of Fig. 1.

a may represent the side of a building, on which is the windmill-tower B , and b the windmill-shaft, from which the pitman c passes to

25 a slide-rod, d , that is fitted for movement in

suitable guides, as usual.

e is a lever hung on a fulcrum, f , at or near its mid-length, and connected at one end by a pin and slot at g , or other connection, to the

30 rod d .

h is the shorter lever, connected at one end by a link, i , to the outer end of lever e , and connected at its other end by a link, l , to a crank on the shaft k . The power is to be taken

35 from this shaft k , and it is provided with a balance-wheel, r .

m is a lever, preferably placed below shaft

k , and connected at one end by a pin and slot, o , to slide-rod d , while its other end is connected by a link, n , to a second crank on shaft 40 k ; or it may be connected to the crank that link l is attached to, link l being connected directly to lever e in this case. The slide-rod d being reciprocated, the movement thereby imparted to levers $e m$ is transferred to the 45 shaft k , and a continuous rotary motion of the shaft is thus obtained. The intermediate lever, h , serves to reverse the direction of the movement given by the lever e ; but the same effect will be produced by having the levers 50 $e m$ of a different order one from the other and connecting the link l directly to the lever e , thus dispensing with lever h .

I do not limit myself to levers of any one order, as they may be arranged as most convenient, according to location. While power can be obtained by the use of either set of levers separately, yet their combined action materially reduces the dead-center resistance and produces a more uniform steady motion. 60

Having thus described my invention, I claim as new and desire to secure by Letters Patent—

1. The combination, with the slide-rod d , of the levers $e m$, links $l n$, and the crank-shaft k , substantially as herein shown and described. 65

2. The combination, with the slide-rod d , the levers $e h m$, the links $i l n$, and the double-crank shaft k , substantially as herein shown and described.

EDWARD S. PLIMPTON.
